(57) **CLAIM**

The ornamental design for an entrance cap, as shown and described.

DESCRIPTION

FIG. 1 is a front view of an entrance cap;

FIG. 2 is a rear view thereof;

FIG. 3 is a right-side view thereof;

FIG. 4 is a left-side view thereof;

FIG. 5 is a perspective view thereof; and,

FIG. 6 is a front view thereof, shown in environmental use. The broken lines shown represent unclaimed subject matter and form no part of the claimed design.

1 Claim, 4 Drawing Sheets---
